Primary Examiner — Jennifer L Watkins(74) *Attorney, Agent, or Firm* — Kilpatrick Townsend & Stockton LLP**CLAIM**

The ornamental design for an orthosis, as shown and described.

DESCRIPTION

FIG. 1 is a side view of an orthosis.

FIG. 2 is another side view of the orthosis of FIG. 1.

FIG. 3 is an isometric view of the orthosis of FIG. 1.

FIG. 4 is a top view of the orthosis of FIG. 1.

FIG. 5 is a front view of the orthosis of FIG. 1; and, FIG. 6 is a back view of the orthosis of FIG. 1.

The broken lines depict portions of an orthosis that form no part of the claimed design.
